REMOVABLE PUMPING MECHANISM

Samuel Allen Guiberson, III, Dallas, Tex., assignor to The Guiberson Corporation, Dallas, Tex., a corporation of Delaware

Application January 27, 1938, Serial No. 187,173

13 Claims. (Cl. 103—234)

The object of the present invention is to provide an intermittent automatically controlled pumping mechanism which may be readily removed from the flow line pipe without the necessity of moving the said pipe.

It has heretofore been proposed to place a valve mechanism in the flow line and in communication with the gas pressures existing between the flow line and the casing. In producing oil from oil wells it is customary, when the gas pressure in the oil-bearing sands is insufficient to expel the oil, to place a flow valve in the flow line and to inject gas into the oil in the flow line at various points.

It has heretofore been proposed to provide a chamber in the bore-hole. The head of the oil is permitted to build up in the chamber by the formation pressure until the head becomes sufficiently great to open a valve against the pressure of a supply of high-pressure gas introduced between the casing and the flow line. At this time, a return valve is closed so that the oil within the chamber cannot be forced back into the formation and the oil in the chamber is aerated so that it moves to the surface.

So far as I know, in all such structures which have heretofore been proposed, it is necessary to pull the entire flow line in case it is desired to remove the valve mechanism. One of the objects of this invention is to provide a mechanism so designed that the valve mechanism may be removed without disturbing the flow line.

The nature of the present invention will be better understood from the accompanying drawing which illustrates a vertical cross sectional view through a portion of a well in which the valve mechanism is inserted.

It has heretofore been proposed to provide a casing 10 and a flow line or tubing 11. The upper end of the casing is provided with the well-known pressure gauge, gas inlet, and valve, not shown. The flow line or tubing 11 terminates near the lower end of the casing and has secured thereto a housing 12, provided with a gas inlet port 13. A barrel 14 is connected to the housing 12 by means of a joint 15, and at the lower end of the barrel is a joint 16 which receives a valve member 17 provided with a valve inlet 18 which inlet may be closed by a ball valve 19. The barrel 14 forms an enlarged chamber 20.

The housing 12 is provided with a central bore 21 which is of approximately the same size, but in no case is it any larger than the inside dimensions of the flow line 11. Within the bore 21 and above the inlet port 13 are packers 22 and

23, but if desired, one packer may be used, which packers are positioned beneath a shoulder 24 and above a shoulder 25 and surround, in packing engagement, a reduced portion 26 of a pull member 27. The pull member 27 at its upper end is provided with a cone-shaped grab member 28, the cone having its vertex extending upwardly and the bottom of the cone forming a shoulder 29 so that if a wire line having a grab is lowered through the tubing, the lower ends of the arms 10 of the grab will be moved outwardly by means of the cone shape of the grab member 28 until the arms of the grab pass beneath the shoulder 29, at which time, the said arms will be moved inwardly beneath the shoulder 29 so that the pull member 27 and all parts carried thereby can be moved upwardly through the flow line.

The pull member 27 is provided with a gas passageway 30 which communicates with the space 39 between the pull member 27 and the housing 12, and below the upper packer and above a lower packer 3 which packer 3 makes a seal between the housing 12 and pull member 27. The member 27 is reduced in circumference adjacent the packer 3 so as to hold the said packer in position. The gas passageway 30 communicates with a passageway 32 in a pipe 33 which is secured to the pull member 27. A valve housing 34 is secured to the lower end of the pipe 33 and intermittent valve mechanism 35 is secured in the valve housing 34. The intermittent valve mechanism forms no part of this invention.

The housing 12 is provided with a passageway 36 which at its upper end communicates with the interior of the housing 12 above the upper packer 22 so that the passageway 36 is in full communication with the interior of the tubing 11. At its lower end the passageway 36 communicates with the enlarged chamber 20. A packer 37 is interposed between the casing 10 40 and the housing 12 at a point below the inlet port 13 so that no oil can pass upwardly beyond the packer 37 and the gas pressures which may be introduced in the casing above the packer 37 cannot pass below the said packer.

The operation of the device is as follows:

The oil from the formation flows upwardly through the valve inlet 18 unseating the ball valve 19, and continues to flow upwardly through the enlarged chamber 20, passageway 36, into the tubing 11 thereby forming a head. As the head increases, the pressure communicated through the port 38 leading to the intermittent valve mechanism increases and unseats a valve therein. Gas under pressure has been introduced into 55

the casing 10 above the packer 37, and this gas under pressure passes through the inlet port 13 into the space 39 and through the passageways 30 and 32 into the valve housing 34 and through 5 the port 40 therein, so that when the said valve in the valve housing is unseated, which mechanism forms no part of this invention, the gas under pressure will pass outwardly into the chamber 20. This gas is under a greater pressure than 10 the pressure produced by the head of oil. The oil within the chamber 20 is thereby aerated, and the ball valve 19 is pressed against its valve seat so that this gas pressure will not be communicated to the oil-bearing sands and the entire column 15 of oil in the chamber 20, passageway 36, and tubing 11 will be aerated and the oil will flow to the surface.

There would be a tendency for the oil to lift the pull member 27 and the parts carried thereby, none of which are of a greater size than the 20 inside of the tubing 11. In order to overcome any such tendency, I have provided an enlargement 25 41 on the lower portion of the member 27, which enlargement is provided with an upper cam shoulder 42 and a lower cam shoulder 43. When the pull member 27 is initially placed in the housing 12, the lower cam shoulder 43 engages the upper cam surface 44 of a movable plug 45 which is pressed inwardly by means of a 30 spring 46 seated in a bore 47 in the housing 12, and which spring is held at its other end by means of a screw-threaded adjustable plug 48 which is screw-threaded into the said bore. The lower cam shoulder 43, being forced against the 35 upper cam surface 44 of the said plug, moves the plug outwardly against the said tension of the spring 46 so that the lower cam surface 43 may be moved against a shoulder 49 at the lower end of the housing 12, at which time the plug 45 is 40 moved inwardly by means of the spring 46 so as to engage the upper cam shoulder 42 and hold the member 27 in the position shown in the drawing. If however, the wire line and grab were lowered through the tubing, so that the arms of 45 the grab were beneath the shoulder 28, and if the wire line were then pulled upwardly, the upper cam shoulder 42 would move the plug 45 outwardly against the tension of its spring and the pull member 27 together with the packers 50 thereon, the enlargement 41, the pipe 33 and the valve housing 34 together with the valve mechanism in the housing could be pulled upwardly through the tubing 11, all of the parts within the housing 12 being of no greater dimensions than the inner dimensions of the flow line 11, and the pipe 33 and valve housing 34 being 55 smaller than the lower portion of the housing 12. In this way, the entire valve mechanism may be removed without disturbing or having to pull the flow line.

I realize that many changes may be made in the specific form of the invention which is shown by way of illustration and not by way of limitation in the accompanying drawing, and I therefore 60 reserve the right to make all changes in the specific form thereof, except as I may limit myself in the following claims.

Having now described my invention I claim:

1. In combination with a flow line, a housing 65 secured to said flow line, a barrel secured to said housing and having a greater inner diameter than said housing, said barrel serving as an oil reservoir, said housing having a by-pass communicating with the barrel and the flow line, a 70 pull member mounted in the housing and ex-

tending into the said barrel, said pull member having no greater outer dimensions than the inner dimensions of said flow line and housing and provided at its upper end with a grab member whereby said pull member may be pulled upwardly through said housing and flow line, said 75 pull member having means through which pressure fluid flows to discharge the contents of said barrel and means to supply said pressure fluid to said last-named means.

2. In combination with the flow line, a housing secured to the flow line and having an internal bore of no greater diameter than the inside diameter of the flow line and in alignment therewith, a barrel secured to the housing and having a greater diameter than the internal diameter of the flow line and housing, a pull member including an intermittent valve member mounted in the housing and projecting into the barrel and provided at its upper end with a grab member whereby said pull member may be pulled upwardly through said housing and flow line, means including a passageway through the pull member whereby compressed gas may be conducted to said intermittent valve member, said intermittent valve serving as a means to admit gas under pressure into said barrel, said housing having a by-pass leading from said barrel and communicating with said flow line.

3. In combination with a flow line, a housing secured to the flow line and having an internal bore of no greater diameter than the inside diameter of the flow line and provided with a port, a barrel attached to and extending below said housing, a pull member mounted in the housing and extending into said barrel, said pull member including an intermittent valve member in that part of the pull member within the barrel, said pull member being provided with a passageway longitudinally thereof and communicating 40 with said intermittent valve mechanism and said port and provided at its upper end with a grab member whereby said pull member may be pulled upwardly through said housing and flow line, said intermittent valve serving as a means to admit gas under pressure into said barrel, said housing having a passageway from said barrel and communicating with the flow line above the pull member.

4. In combination with a flow line, a housing 50 secured to the flow line and having an internal bore of no greater diameter than the inside diameter of the flow line and in alignment therewith, an internal shoulder on the lower end of said housing, a pull member mounted in the bore 55 of said housing above said shoulder, means including said pull member to supply a pressure fluid to aerate oil in the flow line, said pull member being provided with an external collar normally seated on said shoulder, means whereby 60 said pull member may be pulled upwardly through said housing and flow line, and means tending to resist any upward movement of said collar away from said shoulder, said means including a spring pressed plug normally over- 65 riding a cam surface on said collar.

5. In combination with a flow line, a housing having an internal bore of no greater diameter than the inside diameter of the flow line and in alignment therewith, a barrel secured to said housing, said barrel having a greater diameter than the internal diameter of said housing and flow line, a pull member mounted in the housing including an intermittent valve which is in communication with a space in the chamber and a 70

space outside of said housing, said housing being provided with a bypass communicating with the inside of said flow line and the said chamber, said pull member being provided at its upper end with a grab member whereby said pull member may be pulled upwardly through said housing and flow line.

6. In combination with a flow line within a casing, a housing having an internal bore of no greater diameter than the inside diameter of the flow line and in alignment therewith, said housing being provided with a port communicating with a space between the flow line and casing and with the inside of said housing, packing between 10 said housing and casing located below said port, an enlarged chamber secured to said housing, an elongated member carrying an intermittent valve, said intermittent valve being located within said chamber and in communication therewith, said 15 member being provided with a bore in communication with the inside of said housing and with said port, packing interposed between said housing and elongated member above and below said port, said housing having a bypass communicating 20 with said chamber and with the inside of said flow line, said elongated member being provided at its upper end with a grab member whereby said elongated member, the packing within said housing and the intermittent valve may be pulled 25 upwardly through said housing and flow line.

7. A well flowing device for a well having a well tubing in which a standing liquid level is present including, an axial conductor located within the tubing and extending downwardly in the well liquid, means for removably locking the conductor in the tubing, means for introducing a lifting gas into the upper end of the conductor from outside the tubing, and means for admitting the gas from the conductor into the tubing below 30 the liquid level to displace and aerate the liquid and raise the same in the tubing.

8. A well flowing device for a well having a well tubing in which a standing liquid level is present including, an axial conductor located within the tubing and extending downwardly in the well liquid, means for removably locking the conductor in the tubing, means for introducing a lifting gas into the upper end of the conductor from outside the tubing, means for admitting the gas 40 from the conductor into the tubing below the liquid level to displace and aerate the liquid and raise the same in the tubing, and a by-pass around the gas inlet leading to the conductor for by-passing the upwardly flowing well liquid 45 around the inlet.

9. A well flowing device for a well having a well tubing in which a standing liquid level is present including, an axial conductor located within the tubing and extending downwardly in the well liquid, means for introducing a lifting gas into the upper end of the conductor from outside the tubing, a flow valve on the lower end of the conductor for controlling the admittance of the lifting gas into the liquid column for dis- 50 placing and aerating said liquid column and lifting said liquid in the tubing, and means for re-

movably locking the conductor within the tubing, whereby the flow valve carried thereby may be readily removed.

10. A well flowing device for a well having a well tubing in which a standing liquid level is present including, a support adapted to be lowered within and removed from the well tubing, means for locking the support in its set position, a flow valve carried by the lower end of the support and adapted to be submerged in the well liquid, means for conducting a lifting gas to the flow valve through the support, whereby the valve controls the admittance of the gas to the well liquid to displace and aerate the liquid column and lift the same upwardly in the well tubing, and a by-pass around the support and gas inlet for conducting the well liquid therearound in an unrestricted flow through the tubing as it is raised to the surface.

11. A well flowing device for a well having a well tubing in which a standing liquid level is present including, a support adapted to be set within and removed from the well tubing, means for locking the support in its set position, a flow valve carried by the lower end of the support and adapted to be submerged in the well liquid, a conductor removably connected to the valve and to the support for coupling these parts together, said conductor spacing the valve from the support so as to locate the valve in a desired position within the well liquid, means for conducting a lifting gas to the flow valve through the support, whereby the valve controls the admittance of gas to the well liquid to displace and aerate the liquid column and lift the same upwardly in the well tubing, and a by-pass around the support and gas inlet for conducting the well liquid therearound in an unrestricted flow through the tubing as it is raised to the surface.

12. A well flowing device for a well having a well tubing in which a standing liquid level is present including, a supporting element adapted to be run into and removed from the tubing through the bore of said tubing, means for removably locking the element against movement in the bore, a flow valve carried by the lower end of the element and adapted to be submerged in the well liquid, and means for conducting a lifting gas to the flow valve, whereby said valve controls the admittance of the gas to the well liquid to displace and aerate the liquid column and lift the same upwardly in the well tubing.

13. A well flowing device for a well having a well tubing in which a standing liquid level is present including, a supporting assembly adapted to be set within and removed from the well tubing, locking means on the assembly for removably latching the assembly in the tubing, a flow valve carried by the lower end of the assembly and adapted to be submerged in the well liquid, and means for conducting a lifting gas to the flow valve, whereby said valve controls the admission of the gas to the well liquid to displace and aerate the liquid column and lift the same upwardly to the well surface.

SAMUEL ALLEN GUIBERSON, III.
